DESK AND COVER

Ronald H. Beckman, New York, N.Y., assignor to Herman Miller, Inc., Zeeland, Mich., a corporation of Michigan

Filed Nov. 27, 1964, Ser. No. 414,290
2 Claims. (Cl. 312—297)

This invention relates to office furniture, and more particularly to a novel desk, especially a storage type desk, which has a uniquely combined cover means for the work surface.

Office desks or tables usually have a wide assortment of papers and other articles scattered on the working surface during the course of a normal day. To place them in a covered condition at the end of the day is usually advisable, for neatness and cleanliness, and to shield them from "wandering eyes." Since a particular project is rarely finished just at quitting time, however, the papers that are carefully sorted and placed away each evening, must be removed and rearranged the next morning. This is time consuming and inconvenient. It often interrupts a particular thought of procedure pattern, which may be difficult to re-establish if not permanently lost.

Moreover, although it is desirable to replace files in storage to avoid excess cluttering of the desk top, certain files are so frequently used that storage at the desk would be very desirable. Yet, drawers on desks have only limited storage capacity, and normally cannot be left open, for purposes of safety.

Hence, a self-contained desk with integral, handy, storage means and cooperative cover means would be particularly advantageous.

It is an object of this invention to provide just such a desk with novel, handy, integral storage facilities, uniquely combined with novel desk cover means.

Another object of this invention is to provide a desk with unique, integral file storage facilities within arm's length of the desk, and unique retractable desk surface covering means, also within arm's reach, but not interfering with use of the storage facilities.

Another object of this invention is to provide a novel desk work surface cover means convenient to use, yet normally neatly and attractively retracted out of sight when not used. The cover is readily within easy reach to be grasped for use, but does not constitute an obstruction to access to the storage files, or to prevent large papers or books to be spread over the entire desk surface. The desk can even be used as a conference desk with complete perimetral access, to the flat desk top, and perimetral leg room for the conferees. Papers can be left on the desk or table, and yet can be covered from view by passers-by. The cover assembly is relatively inexpensive, and inexpensively and easily mounted. It is neatly retractable out of the way to allow easy access to the storage chamber on the desk, and yet readily available for re-use within convenient reach of the user. It is flexible in all dimensions to enable even larger objects to be covered from sight.

These and several other objects of this invention will become apparent upon studying the following specification in conjunction with the drawings in which:

FIG. 1 is a perspective view of the novel desk;

FIG. 2 is a fragmentary perspective view of the novel desk showing the cover means extended over the work surface and objects thereon;

FIG. 3 is a sectional view of the novel desk taken on plane III—III of FIG. 1; and

FIG. 4 is a sectional view taken on plane IV—IV of FIG. 3.

2

Referring now specifically to the drawings, the complete desk assembly 10 comprises a base subassembly 12, a desk top subassembly 14, a storage subassembly 16, and a cover subassembly 18.

5 The base subassembly 12 may assume a variety of configurations, but preferably has two spaced like pedestals 20 and 22 at opposite ends of the desk, interconnected by a lower tie bar brace and foot rest 24. Each is shaped basically like an H lying on its side. It has an open construction allowing access to the desk from all edges.

The desk top subassembly 14 includes a rigid work panel 28 mounted between pedestals 20 and 22, and resting upon a cross brace 30 (FIG. 3) having its ends affixed to the pedestals. The side edges of panel 28 are secured to a pair of end mounting strips 36 and 38, which in turn are mounted upon pedestals 20 and 22. Preferably, the top work surface 40 of panel 28 has a plastic sheet such as a vinyl layer overlying the panel to 20 form an optimum writing surface.

Mounted at the rear of the desk, slightly spaced from the work surface, is a storage subassembly 16. This includes an elongated storage pod 50 extending the length of the desk, and generally U-shaped in cross-sectional configuration. The pod has a pair of extruded support strips or ribs 52 and 54 on the upper edges. Each rib has a hollow interior with elongated slots 56 extending thereto for receiving adjustable variously spaced, transverse file dividers. Each rib also has a slotted bottom 30 to receive and retain the upper edges of pod 50. The ends of the ribs and the bin or pod are received in correspondingly shaped slots in end panels 58 and 60 at opposite ends of the desk. The vertical panels are mounted to the inside faces of the pedestals.

This storage bin is normally closed by a flipper cover 66, hinged on a pivotal axis 68 along its rear edge to pivot from a lowered closed position, flush with the rest of the desk top (FIG. 3) to the raised open position 35 illustrated in phantom in FIG. 1. Extending generally normal to the underside of the cover is a support ledge 69. This ledge is at an acute angle to the work surface when the cover is open at an obtuse angle to support articles such as books, catalogs, photos, charts, etc. at a convenient viewing relation to the front of the desk. 40 The underside is also preferably covered with a puncturable layer 71 such as cork, to enable items to be tacked in convenient viewing relation. Suitable lock means 70 may be provided between cover 66 and the vertical panel, to 45 provide maximum security for items in the storage file. 50 The cover may be opened by a finger pull 75.

Normally, during use, the storage bin cover is open for ready access to files. The limit of opening of this cover is controlled by suitable means such as stop clip 72 cooperating with a slide bar 74 pivotally mounted on its upper 55 end to the cover. The bar has enlarged free lower end 76 to abut the clip at full open position.

60 Integrally associated with this desk or table is cover subassembly 18. This comprises a flexible wind-up cover element 80 having a width substantially equal to the work area width. The cover element may be formed of a variety of materials such as vinyl plastic, a flexible paper-plastic laminate or many others, such as a woven fabric, which may or may not be plastic impregnated. It is flexible in all dimensions to cover all objects and papers 65 on the desk. It is wound into a roll beneath the desk top, on an elongated bar having an internal coil spring return mechanism 82 like the type normally used for window shades. This coil spring retracting and holding mechanism may be any of conventional assemblies 70 presently used for window shade constructions, as taught for example in United States Patent Nos. 1,278,404; 1,277,

965; and 1,219,100. Since this type of retracting and retention mechanism is conventional, further specific details are not shown since they would only unduly lengthen this description without contributing to the teachings presented herein.

The roll has ends which include a cylindrical projection 84 extending into an opening in pedestal 22 (FIG. 4), and a rectangularly shaped projection 86 extending into a slot in a bracket 88 mounted to pedestal 20 by screws 90. Thus, the center of one end of the bar is held stationary to cock the return coil spring as the roll is unwound. The roll has a conventional pawl-type catch to hold the mechanism in an extended cocked position when the cover is withdrawn to unwind it.

The outer end of cover 80 extends upwardly through a special vertical slot provided between strip 54 and front lip 67 of cover 66 on one hand, and the rear edge of panel 28 and the lower portion of guide 96 on the other hand, as illustrated in FIG. 3. This upper cover end includes an enlarged rod 94 greater in diameter than the slot through which the cover passes, to prevent retraction to a point where it would be inaccessible. This elongated end normally rests in a groove 97 formed by the guide cap element 96.

This cap is attached to the rear edge of panel 28 by integral fasteners 98. It extends upwardly to form its concavity resting in panel notch 100, and then up over and into contact with the work surface. Element 96 is curved around the edge of panel 28 to allow uninhibited cover movement vertically up out of the slot and horizontally over the desk work surface when the cover is pulled forwardly. This curved edge forms a smooth guide surface which keeps the cover straight and smoothes out any wrinkles it might have acquired. Further, it minimizes wear on the cover as it changes directions, and prevents damage to the cover.

The recessed concavity enables the entire cover and its enlarged end to be below the flat desk surface so as to not constitute an obstruction on the desk. In fact, the entire cover is out of sight except for its enlarged end which fits smoothly in its elongated recess.

During normal use of this novel desk, the storage bin is employed for storing files of conventional type, as by utilizing file hangers suspended between strips 52 and 54. It may also be used to receive other articles. For convenience, flipper cover 66 can normally be retained open at the obtuse angle (phantom position illustrated in FIG. 1) for access to the files at arm's length, and to support items at an optimum position. When the day is complete, papers arranged over work surface 40 need not be carefully put away into storage. Rather, end 94 of the cover element is grasped and pulled to draw the flexible cover up through the slot between the storage cover and desk panel, around the curved guide surface, and out over the desk top to the covering condition illustrated in FIG. 2. It covers objects on the desk, whether two or three dimensional, for security and cleanliness. Yet, it does not prevent a large flat work surface or conference surface over the retracted cover. It is quickly and easily operated. It is inexpensive to fabricate and install. Moreover, the cover roll assembly can be dismounted in a moment, if dirty or worn, for example, and replaced by a like, inexpensive assembly. It could even be substituted to suit a change in decor, with only slight expense.

The cover could be locked or latched in extended position if necessary, by securing the outer end to the desk front. This would cause any unauthorized activity with respect to the items covered, to immediately appear suspicious. In extended position, the cover hangs over the

leading edge of the desk, covering the drawers. This is to discourage unauthorized access after the desk has been "closed" by its owner. Preferably, it extends over the front edge of the desk and hangs down substantially, held by a weighted end 77, to cover any drawer suspended between the supports directly beneath the work surface. This discourages unauthorized entry to any part of the desk.

Other advantages will probably occur to those in the art upon studying the foregoing illustrated form of the invention. It is also conceivable that certain details of the structure could be modified within the concept presented. Hence, the invention is not to be limited strictly to the specific and preferred illustrated form shown, but only by the scope of the appended claims and the reasonably equivalent structures to those defined therein.

I claim:

1. An office desk comprising: a support base and a top mounted thereon; said top including a work surface at the front of said desk, with front and back edges; a storage pod suspended on said desk along the back edge of said work surface; an openable cover for said pod; a flexible, wind-up work surface cover, including cover wind-up retraction means beneath said top, adjacent the front of said pod, concealed from above said work surface; an elongated slot opening between said pod and said work surface back edge, said pod cover and said back edge being generally within arm's length of said front edge; said cover having a portion projecting through said slot, and an enlarged edge preventing complete retraction through said slot and providing a grasping pull means readily accessible from said front edge; and said cover being extensible from said retraction means, through said slot, and over the extent of said work surface to cover the work surface and materials thereon.

2. An office desk comprising: a support base including a pair of spaced end pedestals; a pair of vertical end panels mounted to said end pedestals; a desk top suspended between said end panels, and having a work surface with front and back edges; a storage pod suspended between said end panels along said back edge of said work surface; cover means over said pod, openable toward the back of said pod for access to the pod from the front of said work surface; said cover means and pod being within generally arm's length from said front edge; a flexible, wind-up, work surface cover, including cover wind-up retraction means beneath said top adjacent said back edge, adjacent said pod and supported by said end pedestals; an elongated slot opening between said pod and said work surface back edge and generally at arm's length from said front edge; said cover having an end portion projecting up through said slot and having an enlarged edge with a thickness greater than the breadth of said slot, preventing complete retraction back through said slot and providing a grasping pull means; and said cover being extensible from said retraction means over the extent of said work surface to cover the work surface and materials thereon.
